United States Patent Office.

THOMAS H. WITHERBY, OF WORCESTER, MASSACHUSETTS.

Letters Patent No. 101,338, dated March 29, 1870.

IMPROVEMENT IN MOWING-MACHINES.

The Schedule referred to in these Letters Patent and making part of the same.

To all whom it may concern:

Be it known that I, THOMAS H. WITHERBY, of the city and county of Worcester and State of Massachusetts, have invented a new and useful Improvement in Mowing and Harvesting-Machines; and I do hereby declare that the following is a full, clear, and exact description of the construction and operation of the same, reference being had to the annexed drawings making a part of this specification, in which—

Figure 1 is a top view of the machine;

Figure 2 is a side view;

Figure 3, a cross-sectional view; and

Figures 4 and 5 show more in detail the mechanism contained within the shoe and operating the cutting-bar.

The nature of my invention consists in the construction and arrangement of a shoe attached to the forward part of the machine, within which are contained the devices used to operate the cutter-bar, and through which the shaft that drives the machinery runs.

To enable others skilled in the art to make and use my invention, I will proceed to describe its construction and operation, the same letters refer to the same parts in the different positions shown in the several figures.

A^1 is the driving-wheel of the machine, having formed upon its inner side the bevel-gear $J J$.

The axle B connects it with the opposite supporting-wheel A^2 , the frame or platform N being attached to the axle in the usual manner by means of the supports $h h$, through which the axle passes, as seen in fig. 1.

The gearing-shaft C is attached to the axle by means of the sleeve H^1 , and is fastened to the same by the nut i upon the end of said shaft.

The bevel-gear D on the shaft C meshes into the gear J , upon the driving-wheel A^1 .

The shaft C is arranged at right angles with the axle B , and its forward end supported by means of the shoe M , through which it passes, and secured by the nut i on the end of the shaft.

Within said shoe and upon the shaft is the bevel-gear E , so arranged as to connect with and mesh into the bevel-gear F .

This gear F is placed upon a small stud or bearing, l , that passes through it and is firmly secured in the bottom part of the shoe M .

The brace G is connected to the axle B in the same manner as is the shaft C , but at the opposite end of said axle this brace is brought forward at nearly an

angle of forty-five degrees, and attached and secured to the forward end of the shaft C in the same manner as it is secured to the axle, and within the shoe M , in front of the gear-wheel E , washers being used to prevent a direct contact between the brace-sleeve and the gear-wheel.

To the under side of the sleeves H^1 and H^2 is attached a rod, g , and to this rod the lever d is attached, having its fulcrum at x upon the platform N .

By operating this lever the shaft C is thrown in or out of gear with the driving-wheel, at the same time causing the sleeve, to which the brace-rod G is attached, to move with it.

On the bottom side of the shoe M a dovetail groove, K , is formed, within which moves the slide O , fig. 4, corresponding in shape thereto.

Upon this slide are fitted and arranged the two wheels a^1 and a^2 , as seen in fig. 5.

On the stud l , and just below the bevel-gear F , there is rigidly attached to said bevel-gear the cam b , adjusted in line with the wheels a^1 a^2 .

The cutter-bar L is attached to the above slide O , so that, when the machine is in operation, a vibratory motion is imparted to the cutter-bar by means of the gearing referred to and the cam b , a slot, n , being made in the slide, O , through which the stud l passes.

The cutting portion of this machine is hinged upon the shaft C , and its movement controlled, either raised or lowered, by means of the levers e and f , the latter being attached to the lower part of the shoe M , when the former lever e is pressed down, the whole cutting-devices can be raised to a vertical or nearly vertical position, to admit of the machine being drawn from one field to another, as may be desired.

K is the ordinary frame for the support of the cutter-bar fingers, &c., made in the usual way, and the shoe is provided with the wheel C on its bottom side for the purposes of support and facility of movement and transportation.

What I claim as my invention, and desire to secure by Letters Patent, is—

The shoe M pivoted to shaft C , upon opposite sides of gear E , grooved for the reception of the slide O , and supporting the bearing l for the pinion F and cam b , these parts being arranged to operate in the manner and for the purposes herein described.

THOMAS H. WITHERBY.
